CLAIM

The ornamental design for a clone cutter, as shown and described.

DESCRIPTION

FIG. 1 is a front left perspective view of a clone cutter according to this invention;

FIG. 2 is a front right perspective view of the clone cutter shown in FIG. 1;

FIG. 3 is a left side view of the clone cutter shown in FIG. 1;

FIG. 4 is a right side view of the clone cutter shown in FIG. 1;

FIG. 5 is a top view of the clone cutter shown in FIG. 1, the clone cutter being in a closed position;

FIG. 6 is a top view of the clone cutter shown in FIG. 1, the clone cutter being in an open position;

FIG. 7 is a bottom view of the clone cutter shown in FIG. 1;

FIG. 8 is a front view of the clone cutter shown in FIG. 1; and,

FIG. 9 is a rear view of the clone cutter shown in FIG. 1. The shade lines shown represent surface shading and not surface ornamentation, color, or material type. The broken lines in the drawings illustrate portions of the clone cutter and form no part of the claimed design.
